UNITED STATES PATENT OFFICE.

HERMAN L. WAGNER, OF MOUNT VERNON, NEW YORK, ASSIGNOR TO
UNDERWOOD TYPEWRITER COMPANY, OF NEW YORK, N. Y., A COR-
PORATION OF NEW JERSEY.

TYPE-WRITING MACHINE.

No. 848,520.

Specification of Letters Patent.

Patented March 26, 1907.

Application filed May 28, 1906. Serial No. 319,100.

To all whom it may concern:

Be it known that I, HERMAN L. WAGNER, a citizen of the United States, residing in Mount Vernon, in the county of Westchester 5 and State of New York, have invented certain new and useful Improvements in Type-Writing Machines, of which the following is a specification.

This invention relates to type-writing machines in which the type-bars strike against the front side of the platen and are pivoted in an arc below the platen, a slotted segment being usually provided to receive the hub portions of the type-bar.

15 The object of the invention is to provide means for preventing grit and dirt which falls from the platen from gathering in the type-bar pivots or guides and clogging the type-bars.

20 In carrying out my invention I mount a shield over the type-bar pivots, said shield covering the usual slots in the segment, and move the shield back out of the way of the type-bars when the latter are swung up to 25 print. The movement of the shield is effected by the usual universal-bar frame, to which the shield or cover is connected and which moves backward at the latter part of each type-bar stroke.

30 In the accompanying drawings, Figure 1 is a perspective view of a portion of the well-known "Underwood" front-strike writing-machine provided with my improvements. Fig. 2 is a perspective view of the type-bar shield or cover. Fig. 3 is a sectional elevation of platen, type-bar segment, and type-bar. In Fig. 3 a type-bar is shown in normal position, and in Fig. 1 in printing position.

In said Underwood machine types 1 are 40 mounted upon the forward ends of bars 2, pivoted upon a rod 3, mounted in a segment 4, the latter having radial slots 5 to receive the type-bars, and the latter striking against the front side of a platen 6. The platen is 45 supported upon a carriage (not shown) which runs upon a rail 7. The slots 5, it will be seen, are on the lower or peripheral edge of the segment and extend from front to back thereof and are partly open at their tops, 50 owing to the formation of a segmental recess 8 in the front face of the segment-casting immediately above the type-bar guides. The type-bar shield is in the form of a seg- 55 mental sheet-metal flange 9, directly overlying

the slots 5 and normally projecting forwardly, so as to overhang the front face of the segment, Fig. 3, said flange formed on the lower edge of a curved vertical plate 10, which has a top flange 11 underlying a rib or anvil 12, formed on the front face of the segment and adapted to support the type-bars at the instant of printing, Fig. 1.

The parts 9, 10, and 11 all coöperate to prevent access of dust or grit to the type-bar slots 5, whereby the latter are kept clear and constant freedom of action of the type-bars is assured.

The dust-shield is preferably mounted upon a pair of tongues 13, extending forwardly from the usual universal-bar frame 14, said tongues extending through horizontal slots 15, formed in the vertical wall of the segment 4. The shield may be attached to said tongues by means of screws 16 and ears 17, the latter detachably secured to the vertical segmental plate 10. To the frame 14 is fixed the usual segmental universal bar 18 by means of arms 19, formed on the frame and riveted at 20 to ears 21, formed on the universal bar. The latter is operated on the 25 type-bars and at the completion of each printing stroke of the latter moves backward for the purpose of feeding the carriage by the well-known means. The dust-shield, which is fixed to the universal-bar frame, 30 moves back therewith, so as to clear the type-bar when the latter is in printing position, Fig. 1. It will be seen that the curved flange 9 may itself be employed as a universal bar and the segment 18 omitted, the flange 9 being in that case struck by the type-bars and forced back thereby at the last portions of the printing stroke; but the returning-spring and other usual appurtenances of the universal-bar frame may be retained.

Having thus described my invention, I 35 claim—

1. In a type-writing machine, the combination with a system of type-bars pivoted below the platen to strike against the front side thereof, of a segment in which the type-bars are pivoted, said segment having slots to receive the type-bars, a segmental shelf projecting forwardly from the front wall of said type-bar segment, a segmental shield 40 overlying the type-bar slots and having at its rear edge a flange extending up to said shelf and directly beneath the same, and

means for moving said shield back at the type-bar strokes.

2. In a type-writing machine, the combination with a system of type-bars pivoted below the platen to strike against the front side thereof, of a segmental vertical wall having slots in its under edge to receive the type-bars, a segmental shelf projecting forwardly from the front wall of said type-bar segment, 10 a universal bar mounted in rear of said type-bar segment, and having lugs projecting for-

wardly through said segment, and a curved dust-shield in front of the type-bar segment and mounted upon said lugs, and overlying the type-bar slots, and having at its rear edge 15 a flange extending up to said shelf and directly beneath the same.

HERMAN L. WAGNER.
